Attorneys.

UNITED STATES PATENT OFFICE.

GUY WHITE, OF NORTH TONAWANDA, NEW YORK.

MEANS FOR THAWING AUTOMOBILE RADIATORS.

Application filed January 2, 1923. Serial No. 610,897.

To all whom it may concern:

Be it known that I, GUY WHITE, a citizen of the United States, residing at North Tonawanda, in the county of Niagara and State of New York, have invented new and useful Improvements in Means for Thawing Automobile Radiators, of which the following is a specification.

This invention relates to a means for thawing out the radiators of automobiles which utilize the water cooling system.

It is well known to automobile drivers that when a motor vehicle is left standing in the open in cold weather, the water in the radiator becomes frozen, thereby preventing circulation and resulting often in the breakage of the radiator. When the motor is started under such conditions, it takes but a short period of time for the water in the jackets of the motor cylinders to be converted into steam which can be seen issuing from the radiator filler-opening.

It is the chief object of this invention to provide means for utilizing the steam thus generated for thawing out frozen water tubes of the radiator.

A further object is to provide simple and inexpensive means for this purpose which may be applied to old as well as new radiators.

In the accompanying drawings: Figure 1 is a rear view of an automobile radiator embodying my invention. Figure 2 is a top plan view thereof. Figure 3 is an enlarged vertical section taken in the plane of line 3—3, Fig. 2. Figure 4 is an enlarged vertical section on line 4—4, Fig. 1. Figure 5 is a horizontal section on line 5—5, Fig. 3.

Similar characters of reference indicate corresponding parts throughout the several views.

In the embodiment of the invention shown in Figs. 1—5, inclusive, the improvement is shown in connection with a conventional honeycomb type of radiator having upper and lower headers or tanks 10 and 11, water spaces or passages 12 connecting the lower header with the upper header, and the customary air passages 13 disposed between said water spaces.

Applied to the upper and lower ends of one of the water spaces 12 are pipe fittings 14, 15, which are provided with attaching flanges 16 for securing them by soldering or otherwise to the corresponding ends of the radiator shell. As shown in Fig. 5, these

flanges are of the proper dimensions to entirely cover the ends of the water space, so that in the ordinary use of the radiator said space is not utilized as a live passage for conducting the water from the upper to the lower header. The upper pipe fitting 14 is arranged substantially upright and extends approximately to the top of the upper header and preferably below the mouth of the customary filler nipple 17. The lower pipe fitting 15 may be in the form of a rearwardly-facing elbow to which one end of a horizontal pipe 18 is connected, the other end of said pipe passing through an opening 19 in the rear wall of the lower header 11. One end of an L-shaped fitting 20 is connected to the rear end of said pipe 18 while a substantially T-shaped manifold or jet pipe 21 is connected to the other end of said fitting. The horizontal portion of this manifold extends across the lower portion of the radiator and is provided with a series of jet openings 22. As shown in Figs. 2 and 4, said manifold pipe is arranged comparatively close to the lower rear side of the radiator and its jet openings are preferably inclined to direct the steam issuing therefrom forwardly and upwardly or at an angle to the radiator, to permit jets of steam to play against the walls of the water spaces 12.

By this construction, a descending steam conduit is provided which communicates at its upper end with the upper header 10 of the radiator while its lower portion extends across the rear side of the radiator to deliver jets of steam against the radiator.

In operation, assuming the radiator to be frozen and the engine to be running, the water in the cylinder jackets will soon be converted into steam, owing to the interruption of the circulation in the cooling system. The steam thus generated is discharged into the upper header 10 of the radiator through the usual connection between the latter and the engine. Some of this steam enters the upper pipe 14 and passes downwardly through the corresponding water space 12 into the lower pipe fitting 15 and thence to the manifold pipe 21 where it is finally discharged through the jet openings 22 against the lower frozen portion of the radiator core. This steam playing against the walls of the water spaces gradually and uniformly thaws out the radiator without danger of sudden expansion and breaking

or cracking of the radiator. It will be understood that some of the steam entering the upper header also passes through the other water spaces and transmits its heat to the upper portion of the radiator to assist in the thawing out of the same.

Under normal conditions, the steam-conducting passage 12, together with the upper and lower pipe fittings 14 and 15 and the manifold pipe 21, acts in the capacity of an overflow for the radiator.

I claim as my invention:

1. The combination with a radiator for automobiles having an upper header, a lower header and a water passage connecting said headers, of a steam conduit applied to the lower end of said water passage and extending through a wall of said lower header,

the exterior portion of said conduit extending across the radiator and having discharge openings for directing the steam against the same.

2. The combination with a radiator for automobiles having an upper header, a lower header and a water passage connecting said headers, of pipe fittings applied to the upper and lower ends of said water passage and extending into the corresponding headers, and a steam conduit connected to the lower pipe fitting and extending through a wall of said lower header, the exterior portion of said conduit extending across the radiator and having discharge openings for directing the steam against the same.

GUY WHITE.
